Filed June 6, 1961, Ser. No. 65,494

Term of patent 14 years

(Cl. D26—14)

FIG. 1

FIG. 2

FIG. 3

FIG. 4

FIG. 1 is a top perspective view of a portable dictating machine with a top cover in open position and showing my new design.

FIG. 2 is an end perspective view, showing the top cover closed and a cover to an end compartment in open position.

FIG. 3 is a bottom perspective view thereof, showing a carrying handle in its closed position; and

FIG. 4 is a fragmentary view similar to FIG. 3 but showing the carrying handle in extended position.

A fragmentary showing of a carrying strap as well as a showing of a microphone and its attaching cord have been made in broken lines for purposes of illustration. The dominant features of my new design are shown in solid lines.

I claim:

The ornamental design for a portable dictating machine, substantially as shown and described.
